ROLL TOP CONTAINER

Jacques Kreisler, New Rochelle, N. Y.

Application August 16, 1935, Serial No. 36,451

24 Claims.

(Cl. 132—83)

The present invention relates to roll top containers intended especially for use as vanity, cigarette and similar cases.

One object of the invention is to provide a roll top container with a flexible closure of improved construction.

Another object of the invention is to provide a roll top container with a flexible closure constituted by pivotally connected links.

10 Another object of the invention is to provide a container having a plurality of closures, with an arrangement whereby one closure is automatically actuated as a result of the actuation of another closure.

15 Another object of the invention is to provide a roll top container for use as a vanity case and having a powder compartment provided with a closure which is released automatically as the roll top is moved to open position.

20 Another object of the invention is to provide a roll top vanity case with a mirror movably connected to the case, independently of the powder or cosmetic compartments.

25 A further object is to provide a roll top container for use as a vanity case and provided with a mirror which is projected automatically out of the container as the roll top is moved to open position.

A yet further object of the invention is generally to provide a roll top container of pleasing appearance, and to improve the construction and operation of roll top containers.

The above objects of the invention and other objects ancillary thereto will best be understood 35 from the following description considered with reference to the accompanying drawings.

In the drawings:

Fig. 1 is a perspective view of a roll top vanity case embodying the present invention;

40 Fig. 2 is a perspective view of the vanity case, showing the mirror projected and the roll top and powder compartment closure in open position;

Fig. 3 is a longitudinal sectional view on the line 3—3 of Fig. 1;

45 Fig. 4 is a transverse sectional view on the line 4—4 of Fig. 1;

Fig. 5 is a fragmentary sectional view on the line 5—5 of Fig. 2, showing the compartment closure in closed position;

50 Fig. 6 is a perspective view of the container frame in partly assembled relation;

Fig. 7 is a perspective view of the compartment frame and the parts directly associated therewith, showing said frame and parts in disassembled relation;

Fig. 8 is a perspective view of a part of the roll top closure;

Fig. 9 is a fragmentary sectional view on the line 9—9 of Fig. 8;

Fig. 10 is a perspective view of a filler and reinforcing member for the closure member illustrated in Fig. 8;

Fig. 11 is a perspective view of a mirror carried by the closure member illustrated in Fig. 8;

Fig. 12 is a perspective view showing several link elements utilized in constructing the flexible portion of the roll top closure;

Fig. 13 is a fragmentary plan view of the inner surface of the flexible portion of the roll top closure;

Fig. 14 is a transverse sectional view on the line 14—14 of Fig. 13;

Fig. 15 is a transverse sectional view on the line 15—15 of Fig. 13;

Fig. 16 is a fragmentary side view of a roll top 20 container of the present invention, showing a modification;

Fig. 17 is a view similar to Fig. 16, showing the roll top closure in partly open position and the mirror partly projected;

Fig. 18 is a detail sectional view on the line 18—18 of Fig. 17;

Figs. 19 and 20 are views similar to Figs. 16 and 17, respectively, showing another modification of the present invention;

Fig. 21 is a fragmentary longitudinal sectional view of the closure illustrated in Fig. 19;

Fig. 22 is a view partly in elevation and partly in section along the line 22—22 of Fig. 21;

Fig. 23 is a fragmentary transverse sectional view illustrating a modified container frame construction of the present invention;

Fig. 24 is a side view of a frame member utilized in the construction illustrated in Fig. 23;

Fig. 25 is a perspective view of a frame member utilized in the frame construction illustrated in Fig. 23;

Fig. 26 is a view similar to Fig. 23, showing another modification; and

Fig. 27 is a side view of a frame member utilized 45 in the construction illustrated in Fig. 26.

Referring in detail to the drawings, which illustrate the embodiments of the invention in a roll top vanity case, there is shown a metal container frame 10 and a metal roll top closure 14 50 movable in grooves or tracks 16 formed at both sides of the frame at the top and bottom thereof. A powder compartment or tray 18 and a rouge or other cosmetic compartment or tray 20 are mounted in the frame 10 and are normally con- 55

sealed by the roll top closure 14 when the latter is in closed position. The powder compartment 18 is provided with a pivoted closure 22 which is normally held in closed position by a releasable catch 24 and which is provided with a gasket or packing 26 of suitable compressible material such as felt. A mirror 28 is carried by a rigid closure plate 30 which constitutes part of the roll top 14. Said plate 30 is connected at one end 32 to one end of the flexible portion 34 of the closure 14 and at its other end is provided with an upstanding portion 36 which engages one end of the frame 10 and terminates in a free edge 38 which abuts the free end of the flexible portion 34 of the closure 14 when the latter is in closed position. The flexible portion 34 of the closure 14 is constituted by pivoted link elements which will be described later in detail, and the outer surface of the plate 30 is embossed to simulate the link elements of the flexible closure, with the result that the exposed surface of said closure has substantially the same appearance in both its flexible portions and in its rigid portions.

According to one preferred embodiment of the invention, the container frame 10 comprises the parts illustrated in Fig. 6. As here shown, the frame 10 includes a bottom member 40 having upturned ends 42 provided with reduced end projections 44. Said bottom member is provided with longitudinally-extending reinforcing ribs 46 positioned at the sides thereof. Side members 50 are connected to the bottom member 40 by means of the extensions 44 which extend through slots 52 in the end portions of said side members and are swaged or upset to permanently hold said side members in position. The end portions 54 of the side member 50 project equally longitudinally beyond the upturned ends 42 of the bottom member 40, and the edges 56 of said end portions are curved. Longitudinally extending side cap members 58 provided with rims 60 are connected to the side members 50 by plates 62. Said plates 62 are secured to the inner surface of the end caps 58 by solder or other suitable material 63 applied through the apertures 64 in said plates 62, as best shown at the right of Fig. 6. The plates 62 are fastened to the side walls 50 by the struck out tongues 66 which are projected through the slots 68 in said side plates and bent over to hold said plates in position. Said plates 62 are also provided with hollow struck out prongs 70 which are received in spaced openings 72 in the side members 50 in order to accurately position the cap members 58 with respect to the frame walls 50. The side cap members 58 are somewhat larger than the side members 50 so that when the parts of the frame 10 are assembled, the inner periphery 61 of the rim 60 is spaced from the peripheral edge of the side members 50 to provide the tracks or grooves 16 for the roll top closure 14. The parts of the frame thus described may be made of any suitable material, preferably of metal, and for the sake of lightness, the bottom member 40 and the side members 50 are made of aluminum, the end cap member 58 and the plates 62 being preferably made of light brass, the outer surface of said caps 58 being lacquered or enameled or otherwise coated or ornamented.

The powder tray 18 and the cosmetic tray 20 are secured to the frame 10 by a compartment frame member 72 (Fig. 7.) The frame 72 comprises narrow top walls 74 which outline recesses 76 and 78, respectively, within which the trays 18 and 20 are received. Said frame 72 also includes

integral depending outer side walls 80 and integral outer depending end walls 82. The ends of the frame side walls 80 terminate in spaced relation to the end walls 82, forming recesses 83 to accommodate the bent over tongues 66 of the plates 62 when the compartment frame 72 is mounted on the container frame 10. The frame 72 also includes an inner depending end wall 84 integral with the top wall portion 74 as well as inner depending side wall portions 86 positioned at the recess portion 76 of said frame. At the recessed portions 78, there are provided downwardly extending opposed wall portions 88 and 90, respectively, which are integral with the top wall portion 74. When the trays are assembled in the frame 72, the tray 18 is positioned within the recess 76 in frictional engagement with the inner side wall portions of said frame, and is retained in position by inwardly projecting ribs 92 which underlie the lower edges 94 of the wall portions 86. The tray 20 is received within the recess 78 and is retained in position by the frictional engagement between the side walls of said tray and the wall portions 88 and 90 of the frame, it being understood that said wall portions may be arranged in downwardly converging relation to engage the side walls of the tray, and possess sufficient resiliency to resiliently engage the side walls of said tray.

The closure 22 is pivoted to the frame 72 on a pin 96 passing through the closure eye 97 and positioned within a groove 98 with its ends received within spaced bearings 100. The groove 98 is formed by depressing said wall portion 74, and the bearing members 100 are formed by pressing the wall portion 74 upwardly at the ends of the groove. A slot 102 is provided in the wall portion 74 for the passage of the catch 24 which engages the edge of said wall at the opening 102 to releasably hold the closure 22 in closed position. A catch releasing member 104 is pivotally mounted on the wall 80 of the frame 72 (Fig. 5). Said catch releasing member comprises a cam plate 106 having segmental rim portions 108 and 110 and a pin 112. Said catch releasing member is mounted in position in an aperture 114 provided in said wall 80, the plate 106 being located between the inner wall 86 and the outer wall 80 and the pivot pin 112 extending through the aperture 114 and into an aperture 116 provided in the adjacent side frame member 50. The opposite side member is also here shown as provided with an aperture 116, but the aperture in said opposite side wall has no function, and is formed therein merely for the sake of convenience in manufacture, whereby both side walls 50 may be produced by the same die.

The compartment frame 72 is mounted on the container frame 10 in such manner that the side walls 80 are positioned adjacent the inner surfaces of the container frame side walls 50, while the end walls 82 of said frame are positioned adjacent the outer surfaces of the container frame and walls 42. For releasably holding the compartment frame 72 on the container frame 10, detents 118 are provided in each side wall 80 by partially punching portions of said side walls beyond the outer surface thereof, and said detents are received within the hollow prongs 70 when the latter extend within the apertures 72 in the container frame side walls 50.

An important feature of the present invention resides in the construction of the roll top closure 14, a portion 34 of said closure being flexible and the portion of said closure, constituted by the

plate 30, being rigid, and in the case of a vanity or similar case, carrying a mirror 28. The flexible portion 34 of the roll top 14 is constituted by a plurality of pivotally connected links 120 and 122 and an end link 124. The links 120 are channel-shaped, as best shown in Figs. 12 to 15, and constitute the exposed links of the flexible closure portion 34, while the links 122 are flat and constitute connecting links between said links 120. The links 120 are provided with spaced pairs of lateral projections 126 extending from the free ends 121 of the opposite side walls of said links (Fig. 12), and the links 122 have portions 128 displaced from the plane of said links at the same side thereof, said offset portions 128 being provided with slots 130 for the reception of the prongs 126 on the links 120. The links 120 and 122 are assembled in overlapping relation with the prongs 126 of two adjacent links 120 extending through the slots 130 in a connecting single link 122, the prongs being bent over to retain the links in assembled relation. The connecting links 122 are somewhat longer than the links 120 when the two sets of links are assembled. Thus, the links 122 have end portions 134 which extend beyond the ends of the links 120, forming side guides which are received within the grooves 16 in the container frame 10, with the ends of the links 120 in sliding contact with the inner edges 32 of the rims 60 of the caps 58. At the free end of the flexible closure portion 34 adjacent the end edge 38 of the upstanding member 36, when the roll top is in closed position, the endmost link 120 is connected to the flat end link 124 by bending the prongs 126 over said link at the central notch 136 and the end notches 138. It will be noticed that the slots 130 extend for the full length of the offset portions 128 in the connecting links 122 and that by reason of this construction, the links 122 are positioned close to the free edges 121 of the links 120 to keep down the thickness of the flexible closure portion 14, which is, therefore, relatively thin.

The inner end 32 of the plate 30 is provided with projections 140 which are received within the slots 130 in the adjacent connecting link 122, thus securely connecting said plate to the flexible closure portion 34. The plate 30 has longitudinally extending portions 142 which are offset from the outer surface 144 of said plate and are thereby positioned in the same plane as the link portions 134, thus forming continuations of the guides which are movable in the tracks or grooves 16. Said grooves 16 extend completely around the frame at the top, bottom and ends thereof, the top tracks of said grooves being positioned somewhat above the closure and the bottom track of said grooves being positioned somewhat below the bottom 40 of the frame 10, whereby the closure 14, while disposed close to said closure and bottom, is freely movable in said grooves. The bottom tracks of the grooves are provided with entrance slots 17 formed by removing a portion of the rim 60 in each side cap 58. Said entrance slots 17 facilitate the insertion into the grooves 16 of the closure side guides formed by the link extensions 134 and the offset portions 142 of the plate 30. The offset portions 142 are turned over the upper surface 146 of the plate 30, forming longitudinally extending flanges 150 by which the mirror 28 is held. Downwardly bent prongs 151 formed at the ends of said flanges secure the mirror longitudinally of said flanges. An end filler and reinforcing member 152 (Fig. 10) is mounted within the curved end portion 36 of the closure member 30. Said end member 152 is channel-shaped and includes the wall 154 and the flanges 156, said wall 154 being provided with reflexed end portions 158 which conceal the space between the wall 154 and the inner surface 5 of the curved end member 36 when the parts are assembled. The member 152 is secured in position with the lower flange 156 thereof disposed under the ends of the flanges 150 and with the upper flange 156 bearing against the downturned edge 10 37 of the curved closure portion 38. The sides of the curved portion 38 are provided with prongs 160 which are bent over the extension 158 to more securely hold the end member 152 in position.

In accordance with the present invention, provision is made for automatically releasing the closure catch 24 when the roll top 14 is moved to open position, and this is preferably accomplished under the control of said roll top. For this purpose, one of the end flanges 150 is provided with an upwardly reflexed extension 162 which is adapted to engage the rim 110 of the catch release 104 for the purpose of rotating said catch release and bringing the rim portion 110 thereof into engagement with the lower edge of 25 the catch 24 to force the latter out of engagement with the wall portion 74 at the opening 102 in the compartment frame member. It will be observed that the bottom 40 of the container frame 10 is provided with a notch 164 through which the catch releasing rim 110 extends for engagement by the actuating extension 162. Thus, when the present invention is embodied in a vanity case as herein illustrated and the roll top is moved to 30 open position, the mirror 28 is projected externally of the container and the powder box closure is automatically released. The outward movement of the plate 30 is limited by the engagement of detents 162 on the flanges 150 with abutments 40 166 formed on the bottom 40 of the container frame 10 by partially punching portions of said bottom beyond the outer surface thereof adjacent the side members 50 and one end wall 42. It will be understood that the release of the catch 24 permits the closure 22 to move upwardly away 45 from the frame portion 74 at the opening 102 and due to the resilient engagement of the marginal edge portion of said closure with the upper edge 19 of the powder tray 18, said closure moves a substantial distance out of engagement 50 with said edge of the powder tray and can be readily raised to fully open position. The resilient engagement of said closure with the edge 19 of the powder tray also serves to compress the felt gasket 26, forming a tight joint when the closure 55 is in closed position to prevent the escape of powder from the tray 18.

The closure 22 is provided with a peripheral depending rib 27 spaced inwardly of the closure edge 29 which is downturned and thus cooperates with the rib 27 to form a groove within which the gasket 26 is retained. The rib 27 outlines a recess 23 which provides room for a powder puff. In lieu of the felt gasket 36, packing may be provided by a layer of cotton flock adhesively secured in position. This is preferably accomplished in accordance with my invention by depositing a thin layer of glue or other suitable adhesive over the peripheral surface of the closure between the rib 27 and the edge 29 60 and then, while the glue is still wet, depositing a layer of finely divided cotton or other suitable flock thereon by spraying or blowing the same over the glue until a layer of the desired thickness is obtained.

The above described construction of the roll top container is susceptible of various modifications and additions. Thus, for example, as illustrated in Figs. 16 to 18, the cap members 58a of the container frame 10a are provided at the ends thereof adjacent the upstanding end 36a of the closure plate 30a with notches 168 which receive laterally projecting finger pieces 170 which are secured by rivets 172 to the end extensions 158a of the filler member 152a. In other respects, the roll top container construction may be the same as the construction in the above described figures of the drawings. Further, as illustrated in Figs. 19 to 22, a lipstick 174 and an eyebrow pencil 176 may be disposed within the space between the upstanding end member 36a and the end member 152b which, in this case, has a curved wall 154b to conform to the curvature of the lipstick and eyebrow containers. Said wall 154b is provided with slots 178 to accommodate the finger pieces 180 and 182 on the lipstick and eyebrow containers, respectively. In this construction, the free ends of the lipstick holders constitute finger pieces which are received within the notches 168 in the cap members 58a.

In the construction illustrated in Figs. 23 to 25, the end cap members 58b are provided with inserts 184 which fit into the recess 186 provided in the outer wall of said cap members 58b. The inserts 184 have spaced pairs of projections 188 which extend through slots 190 in the cap members 58b and through similar slots in the side walls 50b of the container frame which is otherwise of the same construction as the container frame 10a, with the further exception that the slots 68 in the side members 50 are omitted, the connecting plates 62 being also omitted as the prongs 188 on the inserts 184 serve to secure the cap members 58b to the side walls 50b and, for this purpose, are bent to overlie the inner wall surface of said side members 50b after the prongs 188 are projected through the openings 190 and the openings in said side members 50b. Also, in this case, the cap members 58b are provided with the hollow prongs 192 for positioning said cap members with respect to the side members 50b of the container frame.

In the construction illustrated in Figs. 26 and 27, the side wall members 50 of the container frame are omitted and instead, the cap members 58c are secured directly to the end walls 42 by the extensions 44 which are received within slots 194 in said cap members 58c and swaged or upset to retain said cap members in position. Inserts 196, similar to the inserts 184, but without the prongs 188 of the latter, are snapped into the recess 198 formed in said cap members 58c. Said cap members 58c are provided with spaced openings 200 which receive the detents 118 on the compartment frame 12. The provision of the inserts 184 and 196, in the modifications illustrated in Figs. 23 to 27, permits various ornamental variations, also in the construction shown in Figs. 26 and 27, the inserts 196 may be made of Celluloid or similar material or of other non-metallic material.

While I have shown and described the preferred embodiments of my invention, it will be understood that the invention is capable of other embodiments and that in the constructions herein shown and described, certain changes and omissions may be made without departing from the underlying idea of the invention. Therefore, I do not wish to be limited to the precise constructions herein disclosed, except as may be

required by the appended claims considered with reference to the prior art.

Having described my invention, what I claim and desire to secure by Letters Patent is:

1. A container having a bottom, a top, and opposed spaced side walls curved at their ends, said side walls having grooves extending along the top of the container and said end and bottom thereof, and a closure having a flexible portion guided for movement in said grooves and a rigid portion also guided for movement in said grooves connected to said flexible portion extending along said bottom and arranged to travel with said flexible portion while the latter moves to open and closed positions. 15

2. A container having a bottom, a top, and opposed spaced side walls curved at their ends, said side walls having grooves extending along the top of the container and said end and bottom thereof, and a closure having a flexible portion guided for movement in said grooves and a rigid portion also guided for movement in said grooves connected to said flexible portion extending along said bottom and arranged to travel with said flexible portion while the latter moves to open and closed positions, said rigid portion being of such length that it is at least partially within said grooves when said flexible portion of the closure is in substantially fully open position whereby said flexible portion may be moved to closed position by exerting pressure on the free end of said rigid portion in a direction toward the curved ends of said side walls. 20

3. A container having a bottom, a top, and opposed spaced side walls curved at their ends, said side walls having grooves extending along said top and said ends and bottom, and a closure having a flexible portion guided for movement in said grooves and a rigid portion also guided for movement in said grooves connected to said flexible portion extending along said bottom and arranged to travel with said flexible portion while the latter moves to open and closed positions, said rigid portion constructed and arranged to carry a mirror and to project the same out of the container when the closure is moved to open position. 40

4. A container having a bottom, a top, and opposed spaced side walls curved at their ends, said side walls having grooves extending along the top of the container and said end and bottom thereof, and a closure having a flexible portion guided for movement in said grooves and a rigid portion also guided for movement in said grooves connected to said flexible portion extending along said bottom and arranged to travel with said flexible portion while the latter moves to open and closed positions, said rigid portion being of such length that it is at least partially within said grooves when said flexible portion of the closure is in substantially fully open position whereby said flexible portion may be moved to closed position by exerting pressure on the free end of said rigid portion in a direction toward the curved ends of said side walls, said rigid portion constructed and arranged to carry a mirror and to project the same out of the container when the closure is moved to open position. 50

5. A container having a bottom, a top, and opposed spaced side walls curved at their ends, said side walls having grooves extending along the top of the container and said end and bottom thereof, and a closure having a flexible portion guided for movement in said grooves and a 60

rigid portion also guided for movement in said grooves connected to said flexible portion extending along said bottom and arranged to travel with said flexible portion while the latter moves to open and closed positions, said rigid portion having an upstanding end portion adapted to overlie one end of the container when the flexible portion is in fully closed position.

6. A container having a bottom, a top, and opposed spaced side walls curved at their ends, said side walls having grooves extending along the top of the container and said end and bottom thereof, and a closure having a flexible portion guided for movement in said grooves and a rigid portion also guided for movement in said grooves connected to said flexible portion extending along said bottom and arranged to travel with said flexible portion while the latter moves to open and closed positions, said rigid portion being of such length that it is at least partially within said grooves when said flexible portion of the closure is in substantially fully open position whereby said flexible portion may be moved to closed position by exerting pressure on the free end of said rigid portion in a direction toward the curved ends of said side walls, said rigid portion having an upstanding end portion adapted to overlie one end of the container when the flexible portion is in fully closed position.

7. A container having a bottom, a top, and opposed spaced side walls curved at their ends, said side walls having grooves extending along the top of the container and said end and bottom thereof, and a closure having a flexible portion guided for movement in said grooves, said flexible portion comprising a plurality of individual links having interengaging portions, and a rigid portion on said closure slidable in the groove at the bottom of said receptacle and connected to an end link for moving said flexible portion to open and closed positions.

8. A container having a bottom, a top, and opposed spaced side walls curved at their ends, said side walls having grooves extending along the top of the container and said end and bottom thereof, and a closure having a flexible portion guided for movement in said grooves, said flexible portion comprising a plurality of links having their ends within said grooves, alternate links having recesses and lateral projections, respectively, the projections fitting into recesses in adjacent links whereby said links are directly connected together for movement as a unit across said top of the container and the curved ends of said side walls.

9. A container having a bottom, a top, and opposed spaced side walls curved at their ends, said side walls having grooves extending along the top of the container and said end and bottom thereof, and a closure having a flexible portion guided for movement in said grooves, said flexible portion comprising a plurality of links having their ends within said grooves, some of said links having spaced apertures therethrough and some of said links having projections aligned with said apertures, the projections on one link being received within the apertures of an adjacent link whereby all of said links are connected together for movement as a unit across said top of the receptacle and the curved ends of said side walls.

10. A container having a bottom, a top, and opposed spaced side walls curved at their ends, said side walls having grooves extending along the top of the container and said end and bottom thereof, and a closure having a flexible portion

guided for movement in said grooves, said flexible portion comprising a plurality of pivotally connected links having their ends received within said grooves and movable as a unit in both directions across the top of the container and the curved ends of said side walls.

11. A container having a bottom, a top, and opposed spaced side walls curved at their ends, said side walls having grooves extending along the top of the container and said end and bottom thereof, and a closure having a flexible portion guided for movement in said grooves, said flexible portion comprising a plurality of links disposed in side by side relation, alternate links having a plurality of apertures and projections, respectively, the projections on two spaced links being received within the apertures in an intermediate link, whereby all of said links are flexibly connected together and movable as a unit across the open top of the container and the curved ends of the side walls thereof.

12. A container having a bottom, a top, and opposed spaced side walls curved at their ends, said side walls having grooves extending along the top of the container and said end and bottom thereof, and a closure having a flexible portion guided for movement in said grooves, said flexible portion comprising a plurality of individual links having interengaging portions, and a rigid portion in said closure slidable in the groove at the bottom of the container and connected to an end link for moving said flexible portion to open and closed positions, said rigid portion having an upstanding free end adapted to engage an end of said container when the closure is in fully closed position.

13. A container having a bottom, a top, and opposed spaced side walls curved at their ends, said side walls having grooves extending along the top of the container and said end and bottom thereof, and a closure having a flexible portion guided for movement in said grooves and a rigid portion also guided for movement in said grooves connected to said flexible portion extending along the bottom of the container and arranged to travel with said flexible portion while the latter moves to open and closed positions, a pivoted closure for the container disposed below said flexible portion, and means under the control of said rigid portion for automatically releasing said pivoted closure when said flexible portion is moved to open position.

14. A container having a bottom, a top, and opposed spaced side walls curved at their ends, said side walls having grooves extending along the top of the container and said end and bottom thereof, and a closure having a flexible portion guided for movement in said grooves and a rigid portion also guided for movement in said grooves connected to said flexible portion extending along the bottom of the container and arranged to travel with said flexible portion while the latter moves to open and closed positions, a releasable closure disposed below said flexible portion, and means under the control of said rigid portion for automatically releasing said last mentioned closure when said flexible portion is moved to open position.

15. A roll top container comprising a container frame having side walls provided with peripheral grooves and a bottom in fixed relation to said side walls between the latter, a compartment frame mounted in said container frame over said bottom and between said side walls, and a closure including a flexible portion guided for move- 75

ment in said grooves over the top of said compartment frame and below said bottom of the container frame.

16. A flexible closure for a container, said closure comprising a plurality of links connected together, some of said links being channel shaped and having spaced pairs of projections extending from the free edges thereof and others of said links having slotted offset portions in alignment with said projections and receiving the latter therethrough whereby the free edges of said channel shaped links are disposed close to the adjacent surfaces of said slotted links, said projections being bent over to secure said slotted and channel shaped links together.

17. A roll top container comprising a frame having side walls provided with grooves and end recesses, a closure having a flexible portion and a rigid portion slideable in said grooves, said rigid portion having an upstanding end adapted to be received between the recessed ends of said side walls, and finger piece members carried by said upstanding end adapted to be received in said recesses.

18. A roll top container comprising a frame having side walls provided with grooves and end recesses, a closure having a flexible portion and a rigid portion slideable in said grooves, a powder tray disposed between said side walls, said rigid portion having an upstanding end adapted to be received between said side walls of the frame, said rigid closure portion at said upstanding end constructed and arranged to carry a lipstick holder having a part adapted to be received with a recess in said side wall when said upstanding end is positioned between the side walls of said frame.

19. A roll top container comprising a frame having side walls provided with grooves and end recesses, a closure having a flexible portion and a rigid portion slideable in said grooves, a powder tray disposed between said side walls, said rigid portion having an upstanding end adapted to be received between said side walls of the frame, said rigid portion constructed and arranged to carry a mirror and to project the same out of the container when the closure is moved to open position said rigid closure portion at said upstanding end constructed and arranged to carry a lipstick holder having a part adapted to be received with a recess in said side wall when said upstanding end is positioned between the side walls of said frame.

20. A roll top container comprising a frame

having side walls provided with grooves and end recesses, a closure having a flexible portion and a rigid portion slideable in said grooves, a powder tray disposed between said side walls, said rigid portion having an upstanding end adapted to be received between said side walls of the frame and constructed and arranged to carry a mirror and to project the same out of the container when the closure is moved to open position.

21. A roll top container comprising a frame having side walls provided with grooves and end recesses, a closure having a flexible portion and a rigid portion slideable in said grooves, a powder tray disposed between said side walls, and a hinged powder-proof closure for said powder tray, said flexible portion of the closure being movable over said hinged closure.

22. A roll top container comprising a frame having side walls provided with grooves and end recesses, a closure having a flexible portion and a rigid portion slideable in said grooves, a powder tray disposed between said side walls, and a hinged powder-proof closure for said powder tray, said flexible portion of the closure being movable over said hinged closure, said rigid portion of the closure having an upstanding end adapted to be received between the side walls of the frame, said rigid closure portion being constructed and arranged to carry a cosmetic-stick holder at said upstanding end.

23. A roll top container comprising a frame having side walls provided with grooves and end recesses, a closure having a flexible portion and a rigid portion slideable in said grooves, a powder tray disposed between said side walls, said flexible portion comprising a plurality of articulated links connected as a unit to one end of said rigid portion, said rigid portion having an upstanding end adapted to be received between said side walls of the frame, said rigid closure portion being constructed and arranged to carry a cosmetic-stick holder at said upstanding end.

24. A roll top container comprising a frame having side walls provided with grooves and end recesses, a closure having a flexible portion and a rigid portion slideable in said grooves, said flexible portion comprising a plurality of articulated links connected at one end as a unit to one end of said rigid portion, a powder tray disposed between said side walls and a hinged powder-proof closure for said powder tray, said flexible portion of the closure being movable over said hinged closure.

JACQUES KREISLER.
